DOCUMENT SORTING DEVICE

August F. Kohles, 1510 Locust, Denver, Colo. 80220

Filed Dec. 11, 1967, Ser. No. 9,718

Term of patent 14 years

Int. Cl. D14—02; D19—99

U.S. Cl. D74—2

FIGURE 1 is an isometric view of a document sorting device showing my new design;

FIGURE 2 is a top plan view thereof;

FIGURE 3 is a side elevational view thereof;

FIGURE 4 is a bottom view thereof; and

FIGURE 5 is an end elevational view of my new design.

I claim:

The ornamental design for a document sorting device, as shown.
